[57] CLAIM

The ornamental design for a integral handle for trash container, as shown and described.

DESCRIPTION

FIG. 1 is a top left front perspective view of a integral handle for trash container showing my new design. The broken lines are for illustrative purposes only and form no part of the claimed design;

FIG. 2 is a top plan view thereof;

FIG. 3 is a bottom plan view thereof;

FIG. 4 is a left side elevational view thereof; the right side elevational view being a mirror image;

FIG. 5 is a front elevational view thereof; and,

FIG. 6 is a rear elevational view thereof.
